UNITED STATES PATENT OFFICE.

ANATOL M. JOSEPHO, OF NEW YORK, N. Y.

MACHINE FOR PRINTING PHOTOGRAPHS.

Application filed May 1, 1924. Serial No. 710,410.

To all whom it may concern:

Be it known that I, ANATOL M. JOSEPHO, a citizen of the Republic of Latvia, and a resident of the city of New York, borough 5 of Manhattan, in the county of New York and State of New York, have invented a new and Improved Machine for Printing Photographs, of which the following is a description.

10 My invention relates to a machine for printing photographs and particularly relates to a machine adapted for quantity production of postcard photographs and smaller photographs at low cost.

15 The general object of my invention is to provide a machine of the indicated character improved in various particulars having in view the convenient placing of a large number of plates in the machine for successive printing in series and their convenient removal, the invention further having in view the proper holding of the photographic paper and the severing of successive portions thereof after printing, whereby to promote efficiency and convenience in the operation of the machine.

20 The nature of my invention and its distinguishing features and advantages will clearly appear as the description proceeds.

25 Reference is to be had to the accompanying drawings forming a part of this specification, it being understood that the drawings are merely illustrative of one example of the invention.

30 Figure 1 is a perspective view of a machine embodying my invention showing the doors open to expose the interior;

35 Figure 2 is a plan view with parts broken away;

40 Figure 3 is a transverse vertical section in a plane indicated by the line 3—3, Figure 2;

45 Figure 4 is a vertical section at right angles to Figure 3 as indicated by the line 4—4, Figure 3;

50 Figures 5 and 6 are details in vertical section in the same plane but looking in the opposite directions as indicated by the respective arrows 5—5 and 6—6 in Figure 3;

55 Figure 7 is a plan view of the sliding plate holder;

60 Figure 8 is a longitudinal section in a plane indicated by the line 8—8, Figure 7;

65 Figure 9 is a plan of the slide frame beneath the plate holder shown in Figure 7;

Figure 10 is a plan view of one of the 55 frames removably supported in the frame shown in Figure 9;

Figure 11 is a detail in inverted plan view showing the pressure device for the paper, the plane of the view being indicated by the 60 line 11—11 in Figure 3.

In carrying out my invention in accordance with the illustrated example a cabinet 15 is provided which in practice is placed against a wall A having a transverse opening a therein through which the printed photographic paper B passes to a basket C which in practice is supported in a dark room at the opposite side of wall A. The cabinet includes suitable lighting means 16 disposed in the cabinet near the bottom, the space in which said lighting means is placed having a front closure 17 to be opened to afford access to the lighting means. A transverse frame 18 at the top of the light compartment affords support for a series of glass plates 19 which in practice are colored glass suited to the density of particular pictures. Said frame 18 has tongues 26 sliding in grooves 27 in cleats 28 on opposite 75 sides of the cabinet. A sliding plate holder 20 is supported on the frame 18 and has guided movement in rabbeted cleats 29 on the cabinet. Said plate holder 20 accommodates a plurality of photographic plates E 80 provision being made in the illustrated example for thirty-two plates in the holder 20. The plates rest in rabbets 21 of frame 20. At the center of the plate holder 20 is a strip 22 having notches 23 adapted to be engaged by a pawl 24 held to the central one of a plurality of vertical partition members 25 above said plate holder.

85 Between the partitions 25 is a series of vertically disposed lenses 30 at the upper 95 ends disposed between the partitions 25 and above the lenses 30 a corresponding series of vertical light tubes 31. The lenses 30 are supported on suitable transverse frame members 32 and beneath the lenses is a shutter 100 plate 33 rigid with a rock shaft 34 having a crank handle 35 to which a cord 36 is attached for rocking the shaft to lower the shutter plate 33 to an approximately vertical position out of line with the lenses 30. To rock shaft 34 is secured one end of a retractile spring 37, the opposite end of which is secured to the cabinet as at 38, whereby 105

the spring will return the shaft 34 and the shutters 33 to the normal position beneath the lenses 30. A door 39 is provided above the shutter plate 33 adjacent to the lenses 30 5 and a second door 40 is provided at the front of the light tubes 31.

At the back of the fixed vertical cabinet 41 a trough or depression 42 is formed and is adapted to receive rolls F of photographic paper B. The paper is adapted to be run over the top of the light tubes 31 so that the paper will be subjected to the light passing upwardly through the tubes 31 from lenses 30. At that side of the light tubes 31, adjacent to the rolls F, is a roller 43 over which the paper runs, and by which the paper is supported. At the opposite side of the light tubes, the paper passes between a pair of rollers 44 and over a platform 45 through 20 the back of the cabinet and through the opening a in the wall A. To prevent buckling of the paper passing over the light tubes 31 I provide a strip 46 having springs 47 at the under side, adapted to rest upon the 25 paper. Said strip 46 is secured by a hinge 47, 48 to a cutter board 49, said board 49 being itself hinged along one edge as at 50. Springs 51 are disposed beneath the board 49 to raise the same after a depression. To 30 the board 49, at the under side is secured a knife 52 which acts adjacent to a fixed knife 53 on a frame member 54 beneath the platform 45. The knife 52 is hinged at its upper end to the board 49 as at 55 and the knife 52 is maintained in proper cutting 35 relation to the fixed knife 53 by reason of a scroll spring 56. The cabinet 15 at the back has an opening 57 leading to the wall opening a and for closing said opening 57 40 a slide 58 is provided normally held in an elevated position by springs 59, the arrangement permitting the slide to be lowered whenever it is desired to close the opening 57.

With the described construction, the rolls 45 F of photographic paper are placed in the depressions 42 and the end of the paper brought over the light tubes 31 beneath the strip 46 and springs 47 and passed between the rollers 44. One of said rollers is equipped 50 with a crank handle 60 for turning it so that the paper may be drawn over the light tubes 31, the cord 36 is then pulled to lower the shutter plate 33, thereby permitting the light 16 to pass through the frame 18 or a 55 glass D thereon and through a series of photographic plates E in the frame 20. The light is now free to pass upwardly through the lenses 30 and to the photographic paper B. When the zones of the paper B disposed 60 over the light tubes 31 have been exposed, the knife board 55 is depressed so that the knife 52 severs the paper and permits it to fall through the openings at 57 and a to the basket C. Any of the severed and exposed 65 portions of the paper collecting at the open-

ings 57 and a may be readily removed by the attendant in the dark room in which the basket C is placed.

Any series of plates E extending longitudinally of the frame 20 may be brought 70 into register with the series of lenses 30. Assuming the frame 20 is positioned as in Figure 3, then the plates immediately at the rear of, latch 24 are in register with lenses 30. The notches 23 in strip 22 are arranged 75 as in Figure 8. As is apparent from Figure 3, each successive series of plates at the rear of the series in register with the lenses 30 may be successively brought into registering position with said lenses by sliding the 80 frame 20 forwardly to bring pawl 24 into the different notches, one notch being provided for each series of plates E. The frame 20 can also be withdrawn from the cabinet 85 and reversed, and thus permit the remainder of the series of plates to be brought into register with lenses 30. The frame 18 may also be moved to bring different series of colored glass panels into register with the lenses 30. In the case of the frame 20 the 90 pawl 24 affords a convenient means for holding the frame in adjusted position, and also serves to enable the operator to accurately find the proper position for said frame in order to bring the desired series 95 of plates E into register with lenses 30.

The numeral 60' indicates the upstanding member on the board 58 which is adapted to be engaged by the hinge top 61 when the latter is closed down for the automatic closing of said door 58 against the tension of the springs 59. The numeral 62 indicates a glass front below the shaft 34 and adjacent the door 39 and thus disposed below the shutter plate 33. Said glass front 62 has in practice 105 a suitable color to prevent any light rays passing therethrough from affecting the printing.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a photographic printing machine, a cabinet, a source of light in said cabinet at the lower portion, a plate holder slidably supported in the cabinet above the source of light and having means to hold a series of plates, a series of vertically disposed lenses above said frame, a second frame beneath the first frame and provided with various colored glasses, said second frame 120 slidable to present a glass of a particular color to a position beneath a plate on the holder to be exposed, shutter means be- 125

- 5 tween the lenses and the first frame, means to hold photographic paper above the lenses, means to cause the paper to travel across the plane of the lenses, and means 50 operable for severing the exposed zone of the paper.
2. In a photographic printing machine, a cabinet, a source of light in the lower portion of the cabinet, a plate holder slidably supported in the cabinet and above the light, a series of lenses above the plate holder, said holder being adapted to support a plate in vertical alignment with each lens, and means to cause photographic 10 paper to travel across the focal plane of the lenses.
3. In a photographic printing machine, a cabinet, a source of light in said cabinet, a plate holder slidably supported in the cabinet and having means to hold a series 20 of plates, a series of lenses disposed at the opposite side of said plate holders from the source of light, said holder being movable to successive positions to successively presented different series of plates in register 25 with the lenses, means for holding photographic paper in the focal plane of the lenses, and means to cause photographic paper to travel across the focal plane of the lenses.
4. In a photographic printing machine, a cabinet, a source of light in the lower portion of the cabinet, an adjustable plate holder above the light, said plate holder being adapted to support different series of plates, a series of vertical tubes within the cabinet and with which either series of plates supported by the plate holder may be brought to register, a lens in each tube, 40 and means for moving photographic paper across the upper ends of the tubes.
5. A photographic printing machine including a series of light tubes, a source of light positioned to direct light beams through said light tubes, lenses disposed in the respective light tubes, a shutter extending across the focal plane of the several lenses, means to cause movement of photographic paper to and from a position over 45 the light tubes, and a plate holder having means to hold a plurality of series of plates, said plate holder being slidably supported to adapt it to be given movement for positioning a given series of plates in 50 register with the lenses.
6. In a photographic printing machine, a source of light, a series of lenses adapted to be positioned to receive light from said source, a series of light tubes through which the light from the lenses may pass, 60 a plate holder interposed between the source of light and the lenses, said plate holder being adapted to support a plurality of series of plates and movable in a plane transecting the focal plane of the lenses whereby either of the series of plates may be brought into register with the lenses, and means to cause movement of photographic paper across the light tubes.
7. In a photographic machine, a series 70 of light tubes, a lens in each tube, a frame adapted to support a plurality of series of plates adjustably arranged in a plane transverse to the focal plane of the lenses and at one end of the tubes, and stop means 75 for indicating when a series of plates carried by the frame is in register with the tubes.
8. In a photographic machine, a series 80 of light tubes, a lens in each tube, a frame adapted to support a plurality of series of plates adjustably arranged in a plane transverse to the focal plane of the lenses and at one end of the tubes, and a stationary pawl adapted to cooperate with notches 85 upon the frame for serving as stop means to indicate when a series of plates carried by the frame is in register with said tubes.
9. In a photographic machine, a series 90 of light tubes, a lens in each tube, a frame adjustably arranged in a plane transverse to the focal plane of the lenses and at one end of the tubes, said plate being adapted to support a plurality of series of plates and permit each series to be separately 95 brought into register with the tubes, a shutter for each tube and disposed between the lenses and plate frame, means for manually operating the shutters, and means whereby photographic paper may be moved 100 across the remaining ends of the light tubes.
10. In a photographic printing machine, photographic printing means, means to draw photographic paper across the plane of the printing means, a depressible board, spring means beneath the board, a knife hinged to the board at the under side and depending therefrom, a fixed knife adjacent the first knife, and spring means acting on the first knife to maintain the same 105 in cutting relation to the second knife.

ANATOL M. JOSEPHO.
